UNITED STATES PATENT OFFICE

BERNARD J. PAULSON, OF WAUWATOSA, WISCONSIN, ASSIGNOR TO O-IGINAL PROD-
UCTS INCORPORATED, OF MILWAUKEE, WISCONSIN, A CORPORATION OF WISCONSIN

DESIGN FOR A BRIDGE STAND

Application filed October 19, 1932. Serial No. 45,417. Term of patent 3½ years.

To all whom it may concern:

Be it known that I, BERNARD J. PAULSON, a citizen of the United States, residing at Wauwatosa, in the county of Milwaukee and State of Wisconsin, have invented a new, original, and ornamental Design for a Bridge Stand, of which the following is a

companying drawing, forming part thereof. The single figure is a perspective view of the article showing my design.

I claim:

The ornamental design for a bridge stand, as shown.

BERNARD J. PAULSON,
